HAIR CURLING IRON

John L. Benty, Sands Point, N.Y., assignor to
The Gillette Company, Boston, Mass.

Filed Jan. 2, 1975, Ser. No. 538,014

Term of patent 14 years

Int. Cl. D28—03

U.S. Cl. D86—10 E

Fig. 2

Fig. 3

Fig. 4Fig. 5Fig. 6FIG. 1 is a perspective view of a hair curling iron showing my new design, the cord shown only partially for ease of illustration;

FIG. 2 is an end view taken on line II—II of FIG. 1;
 FIG. 3 is an end view taken on line III—III of FIG. 1;
 FIG. 4 is a side elevational view thereof;
 FIG. 5 is a bottom plan view thereof; and
 FIG. 6 is a top plan view thereof.

I claim:

The ornamental design for a hair curling iron, as shown and described.
